UNITED STATES PATENT OFFICE.

ABDENAGO ROGGI, OF CHICAGO, ILLINOIS.

LID-OPERATING MECHANISM.

Application filed August 7, 1922. Serial No. 580,349.

To all whom it may concern:

Be it known that I, ABDENAGO ROGGI, a citizen of the United States, residing at Chicago, in the county of Cook and State of Illinois, have invented certain and useful Improvements in Lid-Operating Mechanism, of which the following is a description.

My invention relates to an improvement in lid-operating mechanism, and more particularly to a stay arm operating means for use on phonograph cabinets, trunks or the like, for raising, lowering and holding in place the tops, lids or covers of the same.

One of the objects of my invention is to provide lid-operating mechanism as above described, which will tend to mechanically and automatically raise the top of the cabinet after the raising movement is initially started by hand, and to automatically retard the lowering of the top after an initial lowering movement.

Another object of my invention is to provide means for adjusting said lid-operating mechanism, whereby the positive action, considering weight, and the speed of the raising or lowering operation may be regulated.

Many other objects and advantages of the construction herein shown and described will be obvious to those skilled in the art.

To this end my invention consists in the novel construction, arrangement and combination of parts herein shown and described, and more particularly pointed out in the claims.

In the drawings, wherein like reference characters indicate like or corresponding parts,

Fig. 1 is a sectional view of my device taken on the line 1—1 of Fig. 2;

Fig. 2 is an elevation thereof, the dotted lines showing a change in position; and

Fig. 3 is a sectional view of the same, taken on line 3—3 of Fig. 2.

In the drawings, wherein I have illustrated the preferred embodiment of my invention, 1 indicates the cabinet, trunk, case or the like, which in the present instance we will assume as being the cabinet of a talking machine, while 2 represents the lid or cover for the same, the latter being hinged or otherwise secured at one edge, not shown, to the cabinet.

A bracket or plate, L-shaped in cross section, is arranged with one of its legs 3

secured to the top edge of the cabinet by means of suitable screws 4 or their equivalent fastening means, and the other leg 5 arranged to lie against the inner face of the vertical wall of the cabinet.

A bent lever or link, having arms 6 and 7, is pivoted at one end adjacent the lower edge of the plate 5 by means of a pin 8 or the like, said pivoted end of the link having a lug 9 formed thereon to abut against shoulders 10 and 11 provided on the lower edge of the part 5 as is clearly shown in Fig. 2, and thus provide limits or stops for the pivotal movement of the link. Another stop member 12 is arranged on the part 5 to engage the link prior to the contact of the stop 9 with the shoulder 11. The link 6—7 is formed with an offset portion 13 intermediate its ends for the securement of one end of a tension spring 14 for a purpose to be hereinafter described.

A stay arm or link 15 is pivotally connected at one end 16 to the lid or cover 2 by any suitable or preferred means, and the adjacent ends of both the links are pivotally interconnected by means of a pin 17 or the like, so that when the lid is raised or lowered, both of the links will be moved in unison therewith. An elongated slot 18, having an offset enlargement 19, is formed in the portion 3 of the bracket to provide a guide-way during the movement of the stay arm or link 15 between the full-line and dotted-line positions shown.

An offset portion 20 is provided adjacent the lower edge of the plate 5, and between said offset portion 20 and the leg 3 there is mounted a screw 21, as shown. A nut 22 is threaded on said screw for a purpose to be hereinafter described.

A bar 23, having an elongated slot 24 extending longitudinally thereof, is mounted upon a pivot pin 25 carried by the bracket, said slot having a series of indentations 26 arranged therewith for purposes of adjustment. One end 28 of the bar 23 is arranged to be engaged by the nut 22, and the other end 29 is adapted to have the end of the spring 14 secured thereto so that when the spring is in place, as shown, and connected between the parts 13 and 29, the end 29 of the bar will be pressed upwardly into contact with the nut 22, thus securely holding the bar stationary and exerting an upward stress on the stay arm.

The tension of the spring may be manu-

ally adjusted whenever desired, in order to adjust the device for the weight of the cover, or to accelerate or retard the speed of lowering or raising of the lid by adjusting 5 the nut 22, thereby changing the length of the spring, or by moving the bar 23 laterally of the pivot pin 25 with a different notch 26 in engagement with said pivot pin.

In order to facilitate this last-mentioned 10 mode of adjustment of the bar 23, I have provided one or more lugs 30 along the upper edge of the bar, so that a suitable tool may be inserted through the enlargement 19 of the slot 18 to engage the lugs 30 to 15 move the bar laterally of the pivot pin.

From the foregoing description it will be obvious that when the lid is in the closed position, with the mechanism arranged as shown by dotted lines in Fig. 2, then as soon 20 as an initial lifting movement is given to the lid, the tension of the spring 14 will tend to yieldably assist or accelerate the lifting of the lid so as to raise it automatically until it comes to its fully open position, as shown 25 in full lines in said figure. In order to close the lid, the initial lowering movement is given to the lid, whereupon the spring 14 increasingly retards the normal lowering movement of the lid, acting against the 30 weight of the lid, so as to slowly lower the lid to the position shown in dotted lines.

Having thus described my invention, it is obvious that various immaterial modifications may be made in the same without departing 35 from the spirit of my invention; hence I do not wish to be understood as limiting myself to the exact form, construction, arrangement and combination of parts herein shown and described, or uses mentioned.

40 What I claim as new and desire to secure by Letters Patent is:

1. Lid-operating mechanism comprising a link having one end pivotally connected to a lid, a link operatively pivotally connected 45 at one end to a container, the other ends of said links pivotally interconnected, a tension spring secured at one end to a stationary part and at its other end to said second-mentioned link to yieldably retard the closing 50 of the lid and accelerate the raising thereof, and means operable from the exte-

rior of the container to adjust the tension of said spring.

2. Lid-operating mechanism comprising a bracket adapted to be mounted on a container, a link pivotally connected at one end to a lid, a second link pivotally connected to said bracket, the other ends of said links pivotally interconnected, a bar pivoted intermediate its ends on said bracket, means 55 for adjusting said bar longitudinally of its pivotal axis, and a tension spring connected at one end to said bar and at its other end to said last mentioned link to yieldably retard the closing of the lid and accelerate the 60 raising thereof.

3. Lid-operating mechanism comprising a bracket adapted to be mounted on a container, a link pivotally connected at one end to a lid, a second link pivotally connected to 70 said bracket, the other ends of said links pivotally interconnected, a bar carried by said bracket and movable bodily longitudinally of itself, a tension spring connected at one end to said bar and at its other end to 75 said last mentioned link to yieldably retard the closing of the lid and accelerate the raising thereof, and means for adjustably moving said bar to vary the tension of said spring.

4. Lid-operating mechanism comprising a bracket adapted to be mounted on a container, a link pivotally connected at one end to a lid, a second link pivotally connected at one end of said bracket, the other ends of 85 said links pivotally interconnected, a bar pivoted intermediate its ends on said bracket, but normally prevented from movement, means for adjustably moving said bar laterally of its pivotal axis, and a tension 90 spring connected at one end to said last-mentioned link and at its other end to said bar, whereby the opening of said lid is yieldably accelerated and the closing thereof is yieldably retarded.

In testimony whereof, I have hereunto signed my name in the presence of two subscribing witnesses.

ABDENAGO ROGGI.

Witnesses:

JOHN W. HILL,
RUTH M. EPHRAIM.
